UNITED STATES PATENT OFFICE

127,595

DESIGN FOR A NOSE APPLIANCE OR SIMILAR ARTICLE

Helen C. Vivian, Miami, Fla.

Application December 11, 1940, Serial No. 97,263

Term of patent 7 years

To all whom it may concern:

Be it known that I, Helen C. Vivian, a citizen of the United States, residing at Miami, in the county of Dade, State of Florida, have invented a new, original, and ornamental Design for a Nose Appliance or Similar Article, of which the following is a specification, reference being made to the accompanying drawing, forming a part thereof.

appliance or similar article showing my new design;

I claim:

The ornamental design for a nose appliance or similar article, as shown.

HELEN C. VIVIAN.
